UNITED STATES PATENT OFFICE.

IRA A. MOORE AND THOMAS M. ELY, OF CEDAR RAPIDS, IOWA.

RAILWAY CROSSING GATE.

Application filed December 3, 1924. Serial No. 753,694.

This invention relates to movable barriers set at railway and street intersections, and designed to prevent accidents at such crossings. The object of this invention is to provide an efficient safety gate which is entirely automatic in its operation.

The invention is fully disclosed in the description and claims following, reference being had to the accompanying drawings, 10 in which:—

Fig. 1 is a side elevation, illustrating our improved gate as in use. Fig. 2 is a side elevation illustrating a wheel-operated electric switch located some distance back from 15 the street intersection. Fig. 3 is a similar view of the switch apparatus at the intersection. Fig. 4 is a side elevation of the mechanism for operating the gate, a side or door of the enclosing case being removed.

Fig. 5 shows the principal parts of the 20 same mechanism, a side of its frame being removed. Fig. 6 shows the opposite side of the mechanism shown in Fig. 4. Fig. 7 is an elevation of the same as seen from the 25 right of Fig. 6, but with the gate removed. Fig. 8 shows parts of the gate mounting below the section line 8—8 of Fig. 6. Fig. 9 shows parts of the movable rail and a protective guard rail, in perspective. Fig. 10 30 is a vertical, sectional view of the switch actuating mechanism at the intersection. Fig. 11 is an elevation of the same as seen from the right side of Fig. 10. Fig. 12 is a vertical section, similar to Fig. 10, showing 35 the switch actuating mechanism at one of the approaches to the intersection. Fig. 13 is a fragmentary transverse section of the same at the right of the line 13—13, Fig. 12. Fig. 14 shows diagrammatically the wiring 40 of the system.

Referring to Fig. 1, the numeral 5 denotes a passing railway car, of which a wheel 6 serves as a prime mover of a switch-operating rail 7 (Fig. 2) and others that 45 will be described presently. 8 is the permanent track-rail. To it, on the inner side, this rail 7 is pivoted at 9. The upper face of the rail 7 is formed as a curve throughout the most of its length, so that when the 50 flange of the wheel 6 passes over it, however rapidly, the rail is depressed without a sudden shock. A companion rail 10 is similarly pivoted at 11. The pair of rails are coupled by a member 12, hereafter referred to 55 as the coupler, connecting with the respective rails by links 13. Near each end the

coupler is provided with stop-screws 14 to limit the swing of the coupler with respect to the rails, by abutting them on the under sides. Depending from the middle of the 60 coupler is an arm 15 to engage a switch-lever 16, hereafter more specifically mentioned. From a bracket 17, which may be a part of one of the links, a piston-rod 18 depends, and at its lower end connects with 65 a piston 19 (Fig. 10), to be hereafter more particularly described. Between the head of the cylinder 21 and a collar on the piston-rod is mounted a strong lift-spring 22 to restore the parts to normal position. 70

It will be evident from Fig. 2 that a train approaching the movable rails from the left will first depress the left rail until the swing of the coupler is arrested by the right hand abutment screw, when both rails will 75 descend together. The swing of the coupler carries to the right the switch-lever 16, closing an electric circuit, as will be explained later, to actuate the gate-closing mechanism. But with the train moving in the opposite direction the coupler swings free from the switch-lever, and the circuit at this point is not closed. At the intersection, however, a switch is closed by the train moving in either direction, so the rails 23 may both connect directly with the piston-rod, as shown in Fig. 3.

A guard-rail 24 set adjacent to the movable rails serves mainly to protect the latter from obstruction by falling cinders, coal, or other material that might clog the movement of said rails.

On a firm foundation 25 is securely anchored a case or housing 26 adapted to enclose the mechanism for operating the gate, and to protect it against vandalism or the elements. In practice it is preferred to mount the gate by an axis 27 on bearing brackets 28 projecting from the case, and actuate the gate by a segmental gear 29 95 meshing through one side of the case with a gear 30 inside, carried by a shaft 31. Obviously, however, the latter shaft may be extended laterally, and itself carry the gate. The main advantage in the mounting herein shown is that it provides a bearing each side of the gate, which is of course desirable. A substantial frame 32 carries the shaft 31, and also shafts 33 and 34. To the former is attached a gear 35, and to the other a pinion 36 meshing with the gear 35. The latter shaft also carries a worm-gear 37 en- 100 105 110

gaged by a worm 38 on the shaft of an electric motor 39. To the outer end of the shaft 33 is attached a crank 40, which connects by a link-rod 41 with a longer crank 42 secured to the shaft 31. The cranks are so proportioned that a half revolution of the shaft 33 will impart a quarter revolution to the shaft 31.

The motor-shaft is also provided with a 10 brake-wheel 43, flanked by a pair of depending brake-shoes 44 pivoted at 45. The brake is held normally closed on the brake-wheel by a tension spring 46 connecting the free ends of the brake-shoe arms. The 15 brake is released by the spreading action of a pair of rollers 47 carried by a cross-head 48 attached to a rod 49 slidable in a support 50, and at the other end connecting with the core of a solenoid 51 mounted on the base 20 of the frame. Current through the solenoid draws in the core, thus spreading the brake, and on the breaking of the motor and solenoid circuit the brake acts instantly to stop the motor and the movement of the gate.

25 The gate, in practice, is formed mainly of four long bars 52, suitably connected at the outer end, and the inner ends attached to the arms 53 of a fourfold yoke 54. This is provided with an axis 55 carried by the bearing 56 of the partially geared member 29 above referred to. On this axis is mounted a slidable cam 57 held by a compression spring 58 against a pair of rollers 59 carried by the yoke. A finger 60 extending from the cam is slidable in a groove 61 in the yoke, and prevents the cam from turning. This construction permits the gate to turn sidewise when depressed, so that in the event 40 of a vehicle being caught between gates, it might back out, or go ahead, without injury to the gate or vehicle. When swung either way, the cam and its spring restores the gate to normal position.

45 The gate is adapted for warning, as well as a barrier, being provided in the middle with an arresting sign, such for example as, Stop, illuminated at night, and a warning light at each end.

50 A counterweight 62, adjustable on an arm 63 attached to the projecting axis of the gate serves to balance the structure, and so facilitates its movement from the normal vertical position to a horizontal position, 55 and vice versa.

In the figures of the drawing, 10 to 14, the electrical apparatus is illustrated. Referring to Fig. 10, the numeral 64 denotes a closed receptacle for oil, and which is set 60 in the earth at the road intersection at a point below the meeting of the movable rails. In this oil-tank is set a cylinder, closed at the top and bottom. Through the cap at the top passes the piston-rod above referred to, and to its lower end is attached a valved piston 19, the valve 19^a being held

to normally closing position by a light spring 19^b under the collar 20. This permits the piston to descend very quickly, the oil passing rapidly through ports in the piston. It can only return, however, by 70 providing an escape for the oil above it. For this purpose the cap is provided with a vent 65, which may be of the needle-valve type, for nice adjustment. As oil flows out through this vent it also flows in at the bottom of the cylinder through a small hole 66. This is provided with a simple flap-valve 67, normally open, but closing under the downward plunge of the piston. The object of this construction is to retard the lift 75 of the movable rails, both to prevent a premature breaking of the electric circuit, as will be explained presently, and the clatter and jar that would accompany the rising of these rails in the intervals between the 80 overpassing wheels.

To the piston-rod is attached an arm 68 provided with an insulated contact stirrup 69. This normally lies in the open space between two angled terminals 70, but closes 90 a circuit across them when the piston is a little depressed, and until the piston returns to normal position. This takes place after the last wheel has passed over the intersection and the gate has slowly risen to vertical 95 position.

The dash-pot device for the approaches is practically the same as for the intersection, but a different circuit-closer is provided. A pair of spring terminals, suitably insulated, is attached to one side of the oil-tank. A bridging brush-plate 72 is carried by a radial arm 73 attached to a rock-shaft 74 mounted in bearings 75. To this rock-shaft is connected the switch-lever 16 above mentioned. A swing of the depending arm 15 to the left (Fig. 12) closes the circuit. This switch remains closed until the rail returns to normal position. For this purpose the rock-shaft is provided with a shouldered collar 76, which is engaged by a hook 77 during the closing position of the radial arm. The hook is disengaged at the proper time by a lifting finger 78 carried by the piston-rod, and when the latter is near the upper limit of its movement. A spring 79 draws the hook to latching position, and another spring 80 holds the radial arm down to normal position, its downward movement being limited by stop-pins 81, in a manner so simple as to need no explanation.

110 Provision is made for closing and opening the circuit also by the movement of the gate through about ninety degrees of arc. To the shaft 31 is attached an insulating disk 82 provided with contact segments A, B and C, the first named having a central lobe A' for continuous contact with a brush D, and its arcuate segment being in intermittent contact with a brush E. The other 115 120 125 130

segments are detached, B contacting intermittently with a brush F, and C in like manner with a brush G. For convenience the circuits through these brushes may be closed or opened by simple plug switches X, Y and Z on an insulating block O. A socket S receives the current from its source Q, indicated conventionally in Fig. 14.

The operation of the apparatus is as follows:

Referring more particularly to Fig. 14, and assuming a train to be approaching the intersection from the left—the passing wheel closes the circuit at 71, as explained above. Current then passes through conductor a to the motor 39, thence through conductor a' , contacts D, A, E and switch 71 back to the generator Q. This current is shunted through the branch line c, c' , energizing the solenoid to release the motor brake. The motor now operates the gate mechanism to move the gate to the horizontal position, when the segment A breaks contact with the brush E, and the motor stops. The brush G has then made contact with the segments F and C, when the passing train reaches the switch at the intersection and closes it, current flows through a, a', a'', G, C and D, and the motor operates to restore the gate to the vertical position. The light circuit, which in Fig. 14 is supposed to be open, is closed during the whole depressed position of the gate, the circuit being through e, e', B, C , and the lamps H.

It is to be noted that the approach switch 71 is held closed by the latch, as above described until the latch is released by the return of the movable rail and dash-pot piston to normal position. This insures the complete depression of the gate. Otherwise a single unit of the train, or a short train, might first close the switch, and passing it, the rail might lift and open the switch before the gate reached the horizontal position.

The approach switches are supposed to be set at a greater distance from the intersection than the length of any train. If, however, a train should overlap both the approach and the intersection switches, the only effect would be to give continuous movement to the motor, and the gate would move slowly up and down.

Having thus described our invention, we claim:

1. In crossing-gate apparatus operable by an electric motor, switches in the motor circuit operable by rails depressed by a wheel-flange, a pair of such rails, a coupling therefor provided with a fixed switch-operating lever, an oscillating switch engaging said lever on one side and a fixed terminal engaged by said switch as moved in one direction only, whereby the tilt of the coupler closes the switch by the depression of one rail, but not the other.

2. In a crossing-gate apparatus operable by an electric motor, switches in the motor circuit operable by rails depressed by a wheel-flange, a pair of such rails disposed in opposite directions, a coupler pivoted to each near the meeting ends, means to limit the tilt of said coupler, a lever depending from the coupler, and a switch-lever engaged by it on one side only, whereby the depression of one rail closes the switch in its first downward movement, but the switch is not closed by the corresponding movement of the companion rail.

3. In crossing-gate apparatus operable by an electric motor, a motor electric circuit, a switch in such circuit, a wheel-depressible rail to close said switch, a latch to hold the switch closed until the rail returns to normal position, and means connecting with the rail to restore it to normal position, and to release said latch.

In testimony whereof we affix our signatures.

IRA A. MOORE.
THOMAS M. ELY.
